CLAIM

The ornamental design for a combined card tray and cover, as shown and described.

DESCRIPTION

FIG. 1 is a front perspective view of a combined card tray and cover showing my new design;

FIG. 2 is an inverted bottom rear perspective view thereof;

FIG. 3 is a front perspective view of the cover portion;

FIG. 4 is an inverted bottom rear perspective view of the cover portion;

FIG. 5 is a front perspective view of the card tray with the cover removed; and

FIG. 6 is an inverted bottom rear perspective view of FIG. 5.

Fig. 5
